UNITED STATES PATENT OFFICE.

WALTER F. RITTMAN, OF PITTSBURGH, PENNSYLVANIA.

APPARATUS FOR TREATMENT OF HYDROCARBONS.

1,352,916.

Specification of Letters Patent. Patented Sept. 14, 1920.

Application filed August 3, 1917. Serial No. 184,232.

To all whom it may concern:

Be it known that I, WALTER F. RITTMAN, residing at Pittsburgh, in the county of Allegheny and State of Pennsylvania, a citizen 5 of the United States, have invented or discovered certain new and useful Improvements in Apparatus for Treatment of Hydrocarbons, of which improvements the following is a specification.

10 Experience has shown that changing hydrocarbons having a high boiling point to hydrocarbons having a lower boiling point, or to hydrocarbons suitable for motor fuel and gas supply purposes, that those having 15 boiling points above 600 degrees F., on being cracked, disassociate so as to deposit much more carbon than those having boiling points below such temperatures. In other words, when different boiling fractions of any given 20 crude oil are cracked, different conditions of the variables, as temperature, pressure, etc., influencing chemical change, may be necessary and likewise the different fractions 25 would produce different percentages of products such as carbon. The quantities of carbon formed and deposited are of great importance in deciding whether or not a given procedure or method can be employed. Otherwise, mechanical or other means must 30 be provided to remove such carbon so as to not seriously interfere with the operation.

The invention described herein relates to apparatus adapted, in its broader scope, for the treatment of hydrocarbons both above 35 and below 600 F. and also as regards a specific form of such apparatus especially adapted for the treatment of hydrocarbons below 600 F. The invention is hereinafter more fully described and claimed.

40 In the accompanying drawings forming a part of this specification, Figure 1 is a sectional elevation of apparatus embodying my improvements; Fig. 2 is a similar view showing a modification of the lower portion of the form shown in Fig. 1; Fig. 3 is a partly 45 sectional elevation of a modified form of the apparatus and Fig. 4 is a similar view illustrating a modified form of the upper portion of the construction shown in Fig. 3.

50 In the form of apparatus shown in Fig. 1, the retort 1 is arranged within a suitable heating chamber, whereby the walls of the retort may be raised to a temperature sufficiently above the vaporizing temperature of 55 the oil to be treated so as to effect a cracking of the vapors. As shown, the lower end

of the retort extends below the heating chamber and is connected by a pipe 2 to a suitable pump or other source of supply, whereby the oil may be forced into the lower end 60 of the retort under sufficient pressure to maintain the desired height of the column of oil within the retort. In the form shown in Fig. 1, a sufficient quantity of oil is forced into the lower end of the retort to 65 provide a column of such height that the upper portion thereof will lie within the heating chamber and be subjected to sufficient heat to effect a very rapid vaporization of what might be termed a zone of oil at 70 the upper end of the column, of greater or less thickness dependent upon the distance the upper end of the column extends up into the retort. As the vapors are being cracked, they will pass upwardly in the retort and 75 enter the upper end of a tube 3 extending up through the lower end of the retort to a point adjacent to the upper end thereof. This tube or retort is formed of a sufficient diameter relative to the internal diameter 80 of the retort to permit of the flow of vapors down along the same in quantities substantially equal to the rate of vaporization. The lower end of the tube through which the 85 vapors escape from the retort, is connected to a suitable segregation chamber, such as a condenser 4, where a separation of the condensed vapors, solids and fixed gases is effected.

In the operation of this apparatus, only 90 the upper portion of the liquid column in the retort, and that for a relatively small depth, will be sufficiently heated to effect vaporization, and as the heat is applied wholly to the top of the oil, there will be substantially no 95 circulation of the liquid, but the heating thereof will be the result of the upward movement of the body of oil in the heated retort. The principal cracking will occur in the retort, but as the tube, especially the 100 portion in the upper part of the retort, will have a temperature practically the same as that within the retort, cracking will continue as the vapors pass down through the tube. 105

In lieu of maintaining a column of oil in the lower portion of the retort, the upper portion of such column extending up a sufficient height into the heating chamber as to be subjected to a vaporizing temperature, 110 the lower end of the retort may be arranged within the heating chamber and a number

of balls 5 formed of metal or other suitable refractory material, may be arranged within the lower end and the oil fed onto the balls in such quantity relative to the surface of 5 the balls that an instantaneous vaporization will occur. Or if desired, a basket containing these balls may be arranged within the retort at a point where it is subjected to a vaporizing temperature and the oil fed in 10 as shown in Fig. 1, so that the upper portion of the oil will come into contact with these highly heated balls and be instantaneously vaporized.

The form of apparatus shown in Figs. 1 15 and 2 is especially adapted for use in treatment of hydrocarbons having a boiling point below 600 F. as hereinbefore stated, in the treatment of which only a comparatively small amount of carbon will be formed, the 20 vaporizing and cracking temperatures being relatively lower in treating oils below such boiling point. Some carbon will inevitably be formed and adhere to the sides of the retort from which it can be recovered by means 25 known in the art or will drop down into the column of oil at the lower end of the retort so that it will be necessary from time to time to stop the operation of the retort and to blow off the oil in the lower end which has 30 been clogged with carbon, through a pipe 6.

In the form of apparatus shown in Figs. 3 and 4, a retort is arranged vertically in a heating chamber, the retort preferably extending beyond the chamber at its upper end 35 and lower end, as shown. The lower end of this retort is connected by a pipe 7 to a tank or shell 8 such for example as a condenser in which a segregation of the condensable vapors, liquids and solids, passing from the retort 40 from the fixed gases, may be effected. A tube 9 projects up through the lower end of the retort to a point adjacent to the upper end of the latter, the upper end of the tube being open for the passage of liquid into the retort. 45 In the form shown in Fig. 3, the upper portion of the tube 9 is provided with a plurality of small orifices 10, so that the liquid passing up through the tube will be projected in small streams or sprays against the highly 50 heated sides of the retort and through such contact will be practically instantaneously

transformed into a vapor, which passing down through the retort outside of the tube will be cracked and the product resulting from such cracking will flow down into the 55 segregating chamber 8. Suitable means are provided for at the lower end of the tube 9 whereby the liquid hydrocarbons may be forced up through the tube and through the orifices into the retort.

In the construction shown, the lower end of the tube 9 extends into a tank 11, the lower end of the tube being open, or the portion within the tank being perforated for the passage into the tube of liquid which is 65 fed thereunto through a pipe 12 by a pump or other suitable supply under pressure.

I claim herein as my invention:

1. In an apparatus for the treatment of hydrocarbons, the combination of a substantially vertical tubular retort, a tube extending upwardly into said retort, the tube and retort being constructed and arranged to leave an unobstructed annular chamber therebetween, the portion of the tube within 70 the retort having openings for the passage of fluids, means for feeding the hydrocarbon to be treated into the lower portion of one of the foregoing members, means for maintaining vaporizing and cracking temperatures within the retort, and means for segregating the products of cracking connected 75 to the other member.

2. In an apparatus for the treatment of hydrocarbons, the combination of a substantially vertical tubular retort, a tube extending upwardly into said retort and having an opening adjacent to the upper end of the retort for flow of liquid thereinto, the tube and retort being constructed and arranged 80 to leave an unobstructed annular chamber therebetween, the portion of the tube within the retort having openings for the passage of fluids, means for feeding the hydrocarbon to be treated into the lower portion of 85 the retort, means for maintaining vaporizing and cracking temperatures within the retort, and means for segregating the products of cracking connected to the other member.

In testimony whereof, I have hereunto set 90 my hand.

WALTER F. RITTMAN.
